(57) **CLAIM**

The ornamental design for a mouse pad as shown and described.

DESCRIPTION

FIG. 1 is a perspective view of a mouse pad showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of the portion, labeled '8' of FIG. 4.

The broken lines illustrate portions of the mouse pad that form no part of the claimed design.
